Primary Examiner—Cathron Brooks*Assistant Examiner*—Michael A. Pratt(74) Attorney, Agent, or Firm—Banner & Witcoff, Ltd.(57) CLAIM

I claim the ornamental design for a vehicle header, as shown and described.

DESCRIPTION

FIG. 1 is a perspective view of a vehicle header;

FIG. 2 is a top view of the header of FIG. 1;

FIG. 3 is a left side view of the header of FIG. 1;

FIG. 4 is a bottom view of the header of FIG. 1;

FIG. 5 is a right side view of the header of FIG. 1;

FIG. 6 is a rear view of the header of FIG. 1; and,

FIG. 7 is a front view of the header of FIG. 1.

The broken lines in FIGS. 1 through 7 are for illustrative purposes only and form no part of the claimed design.
